SAMUEL V. TENCH, OF LANSFORD, PENNSYLVANIA.

DISCHARGING MEANS FOR JIGS.

1,153,527.

Specification of Letters Patent. Patented Sept. 14, 1915.

Application filed November 29, 1913. Serial No. 803,650.

To all whom it may concern:

Be it known that I, SAMUEL V. TENCH, a citizen of the United States, and a resident of Lansford, county of Carbon, State of Pennsylvania, have invented certain new and useful Improvements in Discharging Means for Jigs, of which the following is a specification.

My invention in its broadest aspect has 10 relation to jigs for the separation of coal from slate or the separation of any other materials having different specific gravities. More particularly, however, it relates to an improved construction of means for dis- 15 charging the materials, such as coal and slate, after the same have been separated in known manner.

The general practice heretofore has been 20 to employ conveyers having flights for carrying the coal and slate from the jig. In the use of such means, however, a considerable percentage of the coal is broken up so that its value is somewhat depreciated, and it is one of the objects of my invention to 25 provide a discharging means by the employment of which such breaking up of the coal will be obviated.

Other objects and advantages of my invention will be specifically referred to in 30 the detailed description of my invention which follows or else will be apparent therefrom.

In the accompanying drawings and for 35 the purpose of rendering my invention more readily understood and comprehended, I have illustrated one form of a convenient embodiment of the same, but it will be understood that changes in the details of construction and in the arrangement of 40 parts may be made within the scope of the claims without departing from my invention.

In the drawings:—Figure 1 is a central vertical section from front to rear of a jig 45 embodying my invention, certain parts thereof being shown in elevation; Fig. 2 is a rear elevation of the same, a part thereof being shown in section; Fig. 3 is a transverse section on the line 3—3 of Fig. 1; and 50 Fig. 4 is a sectional view showing more clearly a detail of construction.

Referring to the drawings, 1 designates a tank supported upon a frame structure 2. The bottom of the said tank is provided 55 with an opening, indicated at 3, for the discharge of mud and other like refuse there-

from. The tank is divided into two compartments, 5 and 6, by means of a partition 7. The said partition terminates a considerable distance above the bottom of the 60 tank, as is indicated in Fig. 1 of the drawings. The bottom of the compartment 5 consists of a perforated jig plate 8 which is secured and held in position in any desired known manner. The said plate is inclined 65 downwardly as is shown in Fig. 1 of the drawings.

9 designates an adjustable baffle plate situated in the compartment 5 and which is inclined downwardly toward the partition 70 7. Said plate 9 is supported from the cross-piece 10. The mixed coal and slate which is to be operated upon is introduced into the space between the baffle plate 9 and the partition 7 constituting a coal inlet. The 75 mixture of coal and slate lodges upon the jig plate 8 and passes underneath the lower edge of the baffle plate 9. The pulsations of the water in the tank and in the compartment 5 are caused by the plunger 15. Such 80 pulsations effect the separation of the coal and slate in known manner. The slate being of higher specific gravity than the coal remains upon the plate 8 and travels downwardly thereon and is discharged at the discharge opening 16. The coal being of 85 lighter specific gravity travels or moves upwardly in the water and falls over the upper edges of the plates 17, 18 and 19. The width of the passage-way 16 for the slate 90 may be adjusted by means of the baffle plate 20 which is secured to the lower ends of the adjustable rods 21 by which it is supported. The plunger 15 is operated by means of a connecting rod 25 having connection with 95 an eccentric 26 upon a shaft 27. This shaft may be driven by any suitable means. Such means, however, is not shown.

The coal which is discharged over the edges of the plates 17, 18 and 19, as above 100 stated, lodges upon the top 30 of a lifting device 31. The said top is inclined outwardly and downwardly and is perforated so that the water may pass therethrough when the said device is lifted by means of 105 the connecting rods 32 as will be later on described. The lifting device 31 is somewhat narrow from front to rear as illustrated, but is of a width or length substantially equal to the width of the tank of the 110 jig. The outer side 33 of the lifting device works against the inside surface of a trans-

verse plate 34 having an outwardly and downwardly inclined flange 35 at its upper edge. The inner upper edge of the inclined top 30 of the lifting device 31 is connected 5 to the plate 19 along a line a short distance below its top edge as shown in Fig. 1 of the drawings. In this way a shallow angular trough or receptacle is provided upon the top of the said lifting device 31 for the purpose of holding a desired amount of coal 10 to be lifted and discharged over the upper edge of the plate 34. The plates 17, 18 and 19 have sliding or telescoping connection with each other by means of pins and slots 15 as is more clearly illustrated in Fig. 4 of the drawings. When the discharging device is lifted lugs 35^a which are secured to the lower edge of the plate 19 travel upwardly in slots 36 in the intermediate plate 18 until 20 they contact with the upper ends thereof after which the plate 18 is also lifted until it reaches the position indicated in said Fig. 4. The plate 17 remains stationary.

For the purpose of operating the connecting rods 32 to raise and lower, that is to reciprocate, the lifting device 31, I have provided a shaft 40 mounted to rock upon the frame 2 which shaft is provided with arms 41 having connection with the upper ends 30 of the connecting rods 32. I have also provided an arm 43 situated at the center of the said shaft which arm is connected to one end of a connecting rod 44, the other end of which is connected to the eccentric 45 mounted at the center of the shaft 27. It will be seen, therefore, that as the shaft 27 rotates it causes a rocking movement of the arm 43 and of the shaft 40 upon which the same is mounted, which in turn causes a 40 rocking movement of the arms 41 secured thereto. Such rocking movement of the arms 41 causes a reciprocating movement of the connecting rods 32 and of the lifting device for causing the discharge of the coal 45 connected to the lower ends thereof.

The slate and stone which are discharged through the opening 16 travel downwardly over the inclined surface 50 and lodge upon the upper sides of the parts 51 and 52.

50 The part 51 is the weight receiving element of a valve tripping mechanism the construction and operation of which will be more fully and specifically described hereinafter.

55 The part 52 may be described as the lifting member of a slate lifting and discharging device. The inner side 53 of said device is elongated and widened as shown so that as the lifting device 52 is raised the said side 53 does not pass out of contact with its adjacent guiding member 53^b. The upper edge of the inside plate 53 of the device 52 extends a short distance above the upper surface of the top of said device so that a receptacle is formed between the said upwardly

projecting edge and the confronting wall of the tank 1.

For the purpose of moving the member 52 upwardly and downwardly to discharge the slate over the upper edge 58 of the rear 70 wall of the tank 1, I have provided a cylinder 60 having a piston (not shown) therein, the connecting rod 60^a of which is secured to a cross bar or beam 61. The opposite ends of said bar or beam are guided in 75 guides 62 upon the opposite parts of the frame work of the structure. Said bar or beam 61 is connected by means of rods 63 to the top of the slate lifting and discharging device 52. It is not necessary that the 80 member 52 be reciprocated continuously because reciprocation at intervals will be sufficient to discharge the slate and stony material which usually constitutes only a small proportion of the mixed coal and slate. 85

Although in the construction illustrated I have shown automatically operating means for causing the actuation and operation of the piston in the cylinder 60 to effect vertical reciprocation of the member 52 and 90 thereby discharge the slate and similar stony material, I desire to point out that my invention in its broader aspect is intended to comprehend other means which may be manually operated for effecting the reciprocation of the piston in the cylinder and the discharging member which is connected thereto.

The means employed by me for effecting the automatic operation of the discharging 100 mechanism consists of the member 51 hereinbefore referred to which is supported normally in the position shown by means of rods 64 which extend through and are suspended upon a cross bar 64^a which is supported upon the frame structure of the apparatus. The upper ends of these rods are provided with nuts and washers 64^a and interposed between the washers and the upper side of the bar 64^a are coiled wire springs 110 65^a. These springs support the rods in the position indicated in Fig. 1 of the drawings in which position the top surface of the member 51 is flush with the inclined upper edge of the guiding member 53^b. As the 115 weight of the slate and other stony material upon the top of the member 51 increases the said member is depressed carrying the said rods 64 downwardly against the resistance offered by the springs 65^a. The said rods 120 64 have connection with a rod 66 so that as they are moved downwardly the said rod 66 is also moved downwardly. The connection between the rod 66 and the rods 64 may be effected in any suitable manner. In the 125 construction shown I have provided a rod 66^a which is secured upon and extends between the rods 64. The rod 66^a is connected to the rod 66 by means of a cross bar or connection 66^b. It will be seen that by rea- 130

son of this connection the rod 66 is depressed or moved downwardly or upwardly in unison with the corresponding movements of the rods 64. The rod 66 is in pivotal engagement at 66^c and 66^e with the outer ends of the arms 66^f and 66^g secured to the pivot rods 66^h and 66ⁱ. The opposite ends of the rods 66^h and 66ⁱ have secured thereto cam levers 67 and 68 with which a tripping member 69 is adapted to contact. The said tripping member is supported upon the rod 60^a hereinbefore referred to. It will be noted that the cam acting arms 67 and 68 extend in opposite directions and toward each other. The upper end of the rod 66 is connected to a lever arm 69^a, movement of which operates a valve (not shown) within the steam chest 69^b. Steam passes from the steam chest 69^b to the lower end of the 20 ton cylinder 60 through a passage-way 69^c and to the upper end of the said cylinder through a passage-way 69^d.

In the position in which the parts are shown the tripping member 69 is in contact 25 with the cam-acting arm 67 of the lower actuating device holding the parts in normal position with the valve in the steam chest closed, and with the tripping member 51 in normal inactive position. When, however, 30 the weight of the slate and other stony matter which piles up upon the members 51 and 52 becomes sufficiently great to depress the member 51 said member is depressed causing a corresponding depression of the rod 66 35 and causing also pivotal movement of the valve actuating lever arm 69^a downwardly or to the left to open the valve in the valve chest to permit the passage of steam into the lower end of the piston cylinder 60. The 40 piston is raised or lifted causing an upward movement of the piston rod 60^a and the cross bar 61 carried thereby. Such upward movement carries the tripping member 69 into contact with the depending cam acting arm 45 68 which has been moved inwardly, that is toward the left, by the downward movement of the rod 66 as before described.

The contact of the tripping member 69 with the inwardly moved cam arm 68 effects 50 outward movement of the latter and lifts the rod 66 upwardly to a position higher than that in which it is illustrated in Fig. 1 of the drawings so as to operate the steam controlling valve in the steam chest 69^b to permit the passage of steam through the passage-way 69^d into the upper end of the piston cylinder 60 so as to cause a return or reverse movement of the piston in the cylinder. Such reverse movement continues 55 until the tripping member 69 again contacts with the cam arm 67 to move it into the position in which it is shown in Fig. 1 of the drawings. In this position the steam controlling valve in the steam chest 69^b is 60 closed and remains closed until the member 65

51 is again depressed against the resistance of the springs 65^c by the weight of the slate and other stony material as hereinbefore described.

The coal which is lifted and discharged 70 over the flange 35 travels over an inclined plate 70 to a trough or run-way 71 inclined as shown and extending transversely of the apparatus and emptying into a coal discharge chute 73.

The slate and other stony material which is lifted by the lifting device 51 is discharged over the outwardly inclined edge 75 of the front wall of the tank into a trough or run-way 75 which is inclined 80 downwardly and transversely of the apparatus as shown in Fig. 2 in the direction opposite to that of the trough or run-way 71 and discharges into a slate discharge chute 76.

In operation the coal and slate or other materials of different specific gravities are separated in the compartment 5 by the pulsating and agitating effect of the water in the tank caused by the reciprocation of the plunger 15. The coal travels to the top of the water in the compartment 5 and overflows the upper edges of the plates 17, 18 and 19 and falls on to the top of the lifting device 31. The said device 31 is lifted in 90 the manner described until the perforated inclined top thereof occupies a position in substantial alinement with the forwardly and downwardly inclined plates 35 and 70 at which time the coal slides forwardly into 95 the trough 71 and is discharged.

The slate is discharged in a similar manner. It moves forward over the plate 8 and over the inclined upper edge 50 of the intermediate wall of the tank and falls on to the 105 inclined top surfaces of the members 51 and 52. Reciprocation of the latter is effected by the operation of the piston in the cylinder in the manner hereinbefore described. When the member 52 in its reciprocations is 110 lifted so that the top thereof is in substantial alinement with the inclined upper edge 58 of the outer front wall of the tank the slate thereon slides into the trough or run-way 75 and is discharged into the chute 76. 115 By the method of lifting and discharging the coal as herein described, a great deal of breakage and crushing is prevented and thus an important item of waste and resultant expense are avoided. Furthermore, 120 by reason of the automatically operating mechanism provided for the purpose of effecting automatically the discharge of the slate or other stony material a great saving in the expense of operation is brought about. 125

I claim:

1. In a jig for separating materials of different specific gravities, as coal and slate, the combination of a receptacle in which the said materials are separated, the said recep- 130

tacle being provided with a passage-way for the discharge of the heavier material, a reciprocating device for discharging the lighter material, means for reciprocating 5 said device, means in front of said device for supporting it, a plate upon the opposite side of said device which plate is supported upon the walls of the said receptacle, a slide- 10 able plate intermediate the first-named plate and said device, the said slideable plate having pin and slot connections with the first-named plate and with the said device whereby when the latter is raised to a position above the first-named plate the inter- 15 mediate plate is lifted to close the space between said first-named plate and said device and thereby prevent passage of coal over said first-named plate.

2. In an apparatus for separating materials having different specific gravities, the combination of separating means, means for continuously discharging one of said materials from the said separating means, means for lifting the other of said materials from 20 said separating means, means normally out of operation for effecting lifting movement of said lifting member, and gravity acting means for placing the last mentioned means in operation.

3. In an apparatus for separating materials having different specific gravities from each other, the combination of means for continuously discharging one of the said materials from the said separating means, 25 means for lifting the other of said materials from said separating means, and means acting automatically to cause lifting movement of the said lifting means at intervals.

4. In an apparatus of the character de- 40 scribed, the combination of a receptacle provided with means for causing the separation of coal from slate and stony matter, means

for continuously discharging the coal from the said receptacle, a member adapted to be moved at intervals for lifting the slate and stony matter and discharging the same from 45 said receptacle and automatically acting means for causing movement of the said member at intervals for the purpose stated.

5. In a machine of the character described, the combination of means for lifting and discharging slate and other like relatively heavy material from a receptacle after it has been separated from lighter material, such as coal, said means comprising a gravity 50 actuated tripping member, a power cylinder, means for opening and closing a valve for controlling the passage of a fluid under pressure into said cylinder, a connection between the said tripping device and the 55 said valve opening and closing means whereby movement of the said tripping device under the influence of gravity occasions the opening in one direction of such valve, a device for lifting the slate, etc. to discharge it from the said receptacle, a connection between the said lifting device and a movable member in the said power cylinder, and means intermediate the connection between the said lifting device and the movable member in said power cylinder and the connection between the said tripping device and the said valve controlling means whereby the latter may be actuated by movement of the connection between the said 60 lifting means and the movable member in the said power cylinder.

In testimony that I claim the foregoing as my invention, I have hereunto signed my name this 13th day of November, A. D. 1913. 65

SAMUEL V. TENCH.

In the presence of—

M. L. WEST,
R. H. HONSBERGER.
